CAN OPENER

Oscar O. Edlund, Burlington, Vt., assignor to
 Edlund Company, Burlington, Vt., a partnership composed of Oscar O. Edlund and Walter W. Edlund

Application March 1, 1941, Serial No. 381,338

3 Claims. (Cl. 30—15)

This invention relates to a can opener and is particularly directed to an improvement in cutting blades.

Various types of can openers have been proposed in which a pointed blade has been provided for penetrating the top of the can with a cutting edge against which the metal is forced for cutting the metal when a rotatable member is operated for revolving the can. The blades were so constructed that a purely cutting action was had which caused friction thereby requiring considerable effort for rotating the can against the action of the blade. Furthermore, during the cutting action the blade had a tendency to scrape the tin off the cut portions which was deposited on the inside of the can.

An object of the invention is the provision of a can opener in which the bead on the can is adapted to be clamped between a rotatable member and a penetrating blade of the opener, the rotatable member being adapted to revolve the can so that the metal of the top of the can will be forced against the shearing edge of the blade for not only shearing the top from the can, but for neatly forcing that portion of the top adjacent the bead, which has not been cut, against the inner wall of the can, the blade being so constructed that it will neatly shear the metal with substantially no discharge of granular metal during the shearing operation.

Another object of the invention is the provision of a can opener having a blade so formed that it will provide a shearing action rather than a cutting action thereby causing less friction when the blade cuts through the tin, the shearing action eliminating scraping of the tin from the severed parts, and thereby eliminating the usual tin deposits which fall upon the contents of the can.

A further object of the invention is the provision of a blade for use in a can opener which will positively shear the metal of the top neatly thereby eliminating tin deposits on the contents of the can, a transverse groove formed in the blade adjacent the shearing edge and opening directly into the shearing edge where said edge comes in contact with the metal of the top when said top is being removed to provide a thin but serviceable knife edge, said blade being curved transversely to provide a convex face to the inner portion of the bead on the can and to that portion of the metal which remains on the top when the center of the top is being cut away so that said rounded or convex portion will slide freely over the remaining portion of the top and

move it into flat contact with the inner walls of the can, the edge of such depressed flange being devoid of sharp edges, thus eliminating the danger of cutting the hands of the operator.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims:

In the drawing:

Figure 1 is an edge view of the shearing knife shown in operative position on a section of a can.

Figure 2 is a vertical section of the knife and can.

Figure 3 is a front view of the cutting blade.

Figure 4 is a rear view of the same.

Figure 5 is a top plan view of the knife shown attached to a supporting member of a can opener.

Figure 6 is a view in perspective of the blade in detached relation.

Figure 7 is a different view in perspective of the detached blade.

Figure 8 is an end view showing the blade fitted to a small can opener.

Figure 9 is a detail view in elevation and partly in section illustrating a conventional turning means for use in conjunction with the can opener shown in Figs. 1 and 2.

Referring more particularly to the drawing, 10 designates the can which has the usual closed top and bottom and which is formed of metal. The top is adapted to be cut by an instrument to provide an opening through which the contents of the can is discharged.

The top of the can is stamped from a single sheet of metal and generally has a U-shaped member as its periphery to engage over the upper edge 11 of the can. This U-shaped member comprises an outer flange 12 which closely contacts the outer wall. A flange 13 engages the inner wall of the can 10 and is connected with the flange 12 by a bight portion 14 whereby the top is supported upon the upper end of the can. The top 15 is integral with the lower edge of the flange 13 so that the top per se is depressed below the upper edge of the can.

The general run of cutters which are employed for cutting the top 15 away from the flange 14

are generally provided with a penetrating point and a cutting edge so that when the penetrating point is forced through the top 15 and a member is revolved, which is in contact with the flange 12 of the top, the can will be rotated so that the top will be cut away, while a portion 16 of the top which remains after the cut has been made is forced towards the inner side walls of the can. However, the cutting action of the blade which is usually of the flat type, not only leaves a rough edge at the lower end of the member 16, but the cutter itself scrapes the tin deposited on the body of the can and this scraped metal falls as deposits on food which finds its way into the mouths of the consumer.

A new type of blade is shown more particularly in Figs. 3, 4, 6 and 7. This blade is provided with a shank portion 20 having threaded passages 21 and 22 whereby threaded bolts or screws 23 and 24 respectively are threaded into these passages for connecting the shank to a depending block or holder 25 which forms part of the can opener not shown. A triangularly shaped blade, usually designated by the numeral 26 depends from the lower end of the shank 20. It will be noted in Figs. 5, 6 and 7 that the shank is convexly curved as indicated by the numeral 27. The blade is likewise curved along the same arc of curvature of the shank 20 as shown more particularly in Figs. 1 and 2 for a purpose which will be presently explained.

The blade, generally designated by the numeral 26, is in the shape of a right angular triangle and is provided with a cutting edge along the hypotenuse of the triangle, while one edge 29 of a transverse groove 30 forms a base of the triangle. The side 31 of the triangle which is at approximately right angles to the base 29, is a continuation of the straight side edge 32 of the shank 20. It will be noted that the shearing edge 28 is cut off at an acute angle and the apex 33 of the triangle is also sheared off at 34 as shown in Figs. 4 and 7 to provide a penetrating point 35.

The groove 30 extends transversely of the blade 26 and extends through the sheared portion 28 which forms the shearing edge and this groove is expanded at this point as shown at 36 to provide a reduced shearing portion as shown at 37 in Figs. 1 and 6.

Since not only the shank 20 is curved transversely so as to provide the convex surface, the blade 26 also has a convex surface 40 which engages the outer face of the portions 16 of the top which remains after the top has been sheared. This rounded surface on the blade limits the frictional contact between the blade and the flange 15 and also provides a means for forcing the remaining portion 16 of the top into contact with the inner wall of the can 10.

In applying the can opener carrying the blade to the top of the can the penetrating point 35 is forced downwardly, and due to the fact that the tip of the blade is sheared as shown at 34 (Fig. 7) the blade will readily penetrate the top 15. As the blade is forced completely into position the metal of the top is sheared by the edge 28. The rotatable member is operated and the can will be revolved since the top of the can and the flanges 12 and 13 are clamped between the blade 26 and the rotatable member 41. When the rotatable member is actuated the can will be revolved and the metal of the top will be sheared by the cutting edge 37 where the narrowest portion of the blade is located. This type of blade will cause a

clean shearing action and eliminates the usual scraping caused by the ordinary forms of blades so that tin deposits are reduced to a minimum.

In the form shown in Fig. 8 a blade 45 is shown 5 in operative relation with a roller 46 of a small hand-operated can opener generally designated by the numeral 47. This blade has an angularly shaped shank due to the difference of construction between this can opener and the one 10 partially illustrated in Figs. 1 and 2. Since the blades are identical in construction the same reference numerals have been applied to this blade and it is not believed that further description of the same is necessary.

15 It will be seen from a careful inspection of the drawings that the shearing edge of the knife 26 is beveled and inclined at an acute angle to the side edge 32 of the shank 20. Thus, that portion of the knife which cuts the top 15 away from the can is biased with respect to a plane passing through the top. Therefore, the blade does not merely cut downwardly through the metal but a gradual shearing action is provided.

20 The shearing action is enhanced by the peculiar formation of the blade where the flared end of the groove 30 enters the knife. The flaring not only provides a thinner shearing edge when the top of the can is removed but the edge curves outwardly from opposite sides of the point 30 of contact so that the metal when being cut is smoothly pressed in opposite directions thereby eliminating to a minimum any metal deposits. The blade shown in Figs. 1, 2 and 9 is attached to the type of cutter described and illustrated in 35 Patent No. 1,713,823 dated May 21, 1929 of H. J. Edlund.

I claim:

1. In a can opener in which the bead on the can is adapted to be clamped between a rotatable member and a penetrating blade of the opener, a blade being in the shape of an inverted right triangle, the downwardly projecting apex of the triangular shaped blade forming a penetrating point, that portion of the blade which 40 forms the hypotenuse of the triangle being beveled to provide a shearing edge, the outer face of the blade being convexly curved transversely of the blade and provided with a transverse groove at the base of the triangle, said groove where it 45 enters the shearing edge forming a reduced portion which is adapted to shear the top from a can.

2. In a can opener in which the bead on the can is adapted to be clamped between a rotatable 55 member and a penetrating blade of the opener, said blade having a convex outer side wall and having the outer and inclined edge which is sheared off at an angle to the outer side in said blade extending from a shank having a convex outer side wall and a downwardly projecting point, the bottom of the blade between the point and shank being inclined at an acute angle to one side edge of the shank, said bottom being beveled to provide a shearing edge, the convex outer side wall having a transverse groove which is flared where it enters the shearing edge to reduce said edge at this point.

3. In a can opener in which the bead on the can is adapted to be clamped between a rotatable member and a penetrating blade of the opener, said blade having a convex outer side wall and having the outer and inclined edge which is sheared off at an angle to the outer side in said 70 blade extending from a shank, having a convex outer side wall and a downwardly projecting

point, the bottom of the blade between the point and shank being inclined at an acute angle to one side edge of the shank, said bottom being beveled to provide a shearing edge, that portion of the shearing edge which progressively shears the top from a can being restricted in thickness

and gradually curving outwardly in opposite directions from the shearing position so that when the metal is sheared the shearing edge will be biased with respect to the plane passing through the top.

5 OSCAR O. EDLUND.
